UNITED STATES PATENT OFFICE.

JOHN JAMES MCLEAN, OF MOOSE JAW, SASKATCHEWAN, CANADA.

INTERNAL-COMBUSTION ENGINE.

1,077,992.

Specification of Letters Patent. Patented Nov. 11, 1913.

Application filed April 4, 1913. Serial No. 758,963.

To all whom it may concern:

Be it known that I, JOHN JAMES MCLEAN, a subject of the King of Great Britain, residing at Moose Jaw, in the Province of Saskatchewan, in the Dominion of Canada, have invented certain new and useful Improvements in Internal-Combustion Engines, and do hereby declare that the following is a full, clear, and exact description 10 of the same, such as will enable others skilled in the art to which it appertains to make and use the same.

This invention relates to improvements in internal combustion engines and the objects 15 of the invention are to increase the amount of power obtainable from each cylinder of the engine, to reduce the number of working parts, to generally improve and simplify the construction of the various parts to better 20 adapt them to perform the functions required of them.

It consists essentially of the improved construction hereinafter described in detail in the accompanying specifications and drawings.

In the drawings: Figure 1 is a plan view of the engine. Fig. 2 is a vertical section through one of the cylinders. Fig. 3 is a perspective detail showing the connection to 30 the pumping mechanism. Fig. 4 is a sectional detail through one of the pumps feeding the combustible. Fig. 5 is a detail showing the igniting means.

In the drawings like characters of reference indicate corresponding parts in all the figures.

Referring to the drawing, A represents the cylinders of the engine, of which any number may be provided and which are 40 preferably disposed horizontally. In accordance with the present invention, each cylinder is open at both ends and pistons C and D are provided in the ends, each piston working from the center to opposite ends 45 and being connected to separate crank shafts E and F or equivalent rotary mechanism, located opposite the open ends of the cylinder, said crank shafts being supported in suitable bearings G and H which rest on the 50 base K. Links 10 connect the pistons with

the crank shafts. Fly wheels L may be provided on the end of the crank shaft.

Combustible is introduced in the center of the cylinders in any suitable way. I have illustrated the pump M of any suitable construction adapted to feed the combustible, which may be a mixture of gasoline and air, through the inlet ports N, the said pump being conveniently operated from a link 12 which connects cranks 13 and 14 on opposite 60 crank shafts and is connected to the pump piston 15 by means of a bent arm 16 having a slot 17 which fits over a pin 18 on the link 12. The exhaust gases may pass simultaneously out both ends through exhaust ports 65 17' and 18'. The passage of the combustible fluid into the pump is controlled by a suitable check valve 22.

The spark plugs 20 may be controlled by suitable means. I have illustrated a pivoted 70 insulated lever 40 pivoted to a bracket 41 on the cylinder and the lower end 42 of which is adapted to be engaged by the connecting rod 12 when raised, the inner end of the lever being adapted to make a circuit 75 through a flexible contact finger 43.

The cycle of operation of the engine will be readily understood.

The combustible gas is forced into the cylinder under moderate pressure when the pistons are near the center. Ignition is caused 80 to take place through suitable spark plugs 20 and the pistons are driven by the expansion in opposite directions, thus utilizing the expansion in both directions of the gases 85 and thereby securing greater economy.

It will be seen that the engine takes up very little room owing to the reduction of the number of working parts. The two crank shafts perform separate work or may 90 be geared together.

As many changes could be made in the above construction and many apparently widely different embodiments of my invention, within the scope of the claim, constructed without departing from the spirit or scope thereof, it is intended that all matter contained in the specification and drawing shall be interpreted as illustrative and not in a limiting sense.

What I claim as my invention is:

An internal combustion engine comprising cylinders open at both ends, two pistons in each of the cylinders movable from the center to opposite ends, two crank shafts, rods connecting the crank shafts with the pistons, means for supporting the crank shafts, a link, cranks on the crank shafts connected to

the link and feeding pumps operatively connected to the link.

In witness whereof I have hereunto set my hand in the presence of two witnesses.

JOHN JAMES McLEAN.
